PIPE BENDING MACHINE

Harvey H. Olsen, Port Richmond, Staten Island,
N. Y., assignor of fifty per cent to Gustav E.
Larson, Brooklyn, N. Y.

Application August 7, 1940, Serial No. 351,705

1 Claim. (Cl. 153—32)

This invention relates to pipe bending machines.

An object of this invention is to provide a strong, rugged and durable pipe bending machine, which shall be relatively inexpensive to manufacture, easy to operate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawings, in which is shown one of the various possible illustrative embodiments of this invention,

Fig. 1 is a side elevational view of a machine embodying the invention, with parts broken away and in cross-section;

Fig. 2 is a front elevational view of the machine shown in Fig. 1;

Fig. 3 is an enlarged, cross-sectional view taken on line 3—3 of Fig. 1;

Fig. 4 is a cross-sectional view taken on line 4—4 of Fig. 3;

Fig. 5 is a cross-sectional view taken on line 5—5 of Fig. 4; and

Fig. 6 is a cross-sectional view taken on line 6—6 of Fig. 4.

Referring now in detail to the drawings, 10 designates a pipe bending machine embodying the invention. The same comprises a frame support 11 provided with front and rear parallel base members 12 and 13, to which there are fixed, as by screws 12a and 13a, parallel, symmetrically disposed, angle shaped members 14 and 15 having upstanding walls 14a and 15a.

Fixed to the upstanding wall 14a of angle shaped member 14, are a pair of vertical, parallel, similar, symmetrically disposed posts 18 of angle shaped cross-section. The posts 18 have side walls 19 and front walls 20.

Fixed to the upstanding wall or flange 15a of angle shaped member 15 are a pair of rear posts 21 having parallel side walls 22 and aligned rear walls 23.

Fixed to the posts 18 and 21, and mounted on the bases 12 and 13, are parallel walls 24 having at their upper ends inwardly extending, horizontal flanges 25. Mounted on the flanges 25, and adjacent the rear posts 21, is a horizontal, transverse plate 26 carrying a block 27 formed at its upper end with a central groove 28 of 50

curved transverse cross-section and inclined downwardly and forwardly.

Fixed to the flanges 25, as by rivets 30, and located in advance of the plate 26, is a horizontal plate 31 formed with two parallel rows of openings 33, for the purpose hereinafter appearing.

Fixed to the upper surface of plate 31, is a member 34 of inverted V-shaped cross-section, located between the rows of openings 33. Fixed to the underside of plate 31, is a member 35, similar and symmetrically disposed with respect to the member 34.

It will be noted that the members 34 and 35 together form substantially a square tube, with the plate 31 passing through opposite corners of the tube. Wound around the tube 34, 35, and passing through the openings 33, is a cable 37, said cable being wound continuously in the manner of numeral 8 a number of times, the lower loop of the numeral 8 passing around the tube 34, 35 and the upper loop of the numeral 8 being located above said tube to form a strap 38. A U-shaped hasp 40 may be passed between the crossing portions of the cable, and fixed by nuts 41 screwed to the threaded ends 42 of the hasp, to keep the cable from unwinding. The outer ends of the cable may be fixed by a clamp 43 of any suitable construction.

The front posts 18 extend to a higher level than the rear posts 21. The upper ends of the rear posts 21 may be connected to the upper ends of the front posts 18 by forwardly and upwardly inclined beams 50. At the juncture of the posts 18 with the beams 50, are bearings 51 supporting a winch 52. The winch 52 comprises a drum 53. On the drum 53 is a doubled cable 54 having a looped end 55. On the axle 6 of the drum is a worm wheel 57. Journalled on brackets 58 which support the bearings 51, is a worm 59 meshing with the worm wheel 57. A crank handle 60 is provided to rotate the worm 59.

The operation of the device 10 for bending pipe 65 will now be described:

The pipe is passed between the posts 21 and 18 in contact with the groove 28. The pipe is also passed through the strap 38. The forward end 66 of the pipe is passed through the looped end 55 of the cable 54. The crank handle 60 is then turned to pull up the end 66 of the pipe, to bend the pipe.

Any suitable markings 70 may be made on the posts 18 to indicate the degree of bending achieved.

It will thus be seen that there is provided a

device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

A pipe bending machine comprising a pair of parallel front and rear base members, a pair of parallel upstanding vertical posts on the front base member, a pair of parallel vertical upstanding posts on the rear base member, aligned with the front posts, the front posts extending to a greater height than the rear posts, means to interconnect the upper ends of the rear posts with the upper ends of the front posts, a pair of parallel plates attached to the front and rear

posts and extending from front to rear, a block mounted on the rear ends of said parallel plates and formed with a longitudinal groove of inclined, curved, transverse cross-section, inclined 5 forwardly and downwardly, a horizontal plate mounted on said parallel plates in advance of said block and formed with two parallel rows of openings, a cable wound continuously through said openings in the form of a numeral 8, the 10 upper loop of the numeral 8 comprising a strap located in advance of the groove and aligned therewith and substantially at the same level, a winch at the upper end of the front posts, said strap being adapted to receive the pipe to be bent, with a portion of the pipe in the groove, and said winch having means to engage another 15 portion of the pipe, means on the front post to indicate the degree to which the pipe has been bent, and means on the upper and lower sides 20 of said horizontal plate about which the lower loop of the numeral 8 is wound.

HARVEY H. OLSEN.
